M.W.Baldwin.

Steam Engine Valve.

No 8900.

Patented Apr 27-1852.

UNITED STATES PATENT OFFICE.

M. W. BALDWIN, OF PHILADELPHIA, PENNSYLVANIA.

VALVE FOR STEAM-ENGINES.

Specification of Letters Patent No. 8,900, dated April 27, 1852.

To all whom it may concern:

Be it known that I, MATTHIAS W. BALDWIN, of the city and county of Philadelphia and State of Pennsylvania, have invented 5 certain new and useful Improvements in Steam-Engines; and I do hereby declare that the following is a full, clear, and exact description of my said invention, reference being had to the accompanying drawing, 10 which forms part of this specification, and in which—

Figure 1 represents a longitudinal section of the steam cylinder and valves of a horizontal steam engine together with the crank 15 shaft and valve gear thereof, Figs. 2 and 3 are views in section showing the relative position of the valves and piston at different portions of the stroke, and Figs. 4 and 5 are views of modified forms of my valve 20 mechanism.

In all engines, but particularly in locomotive engines and others moving at high velocities, it is desirable that the valves which effect the admission and discharge of 25 steam from the steam cylinder should be suddenly opened to their full extent and as suddenly closed, and various attempts have from time to time been made by engineers to accomplish this result.

30 My invention and improvement consists in arranging in a suitable valve chest a duplex valve one part of which is actuated by valve gear in the usual manner, and its office is to admit steam directly from the 35 boiler to actuate the other part which opens and closes the passages for steam to pass into or out of the cylinder. This method of operating the valves is applicable to engines of all descriptions. The mechanism repre-

40 sented at Figs. 1, 2, and 3 in the accompanying drawings, is well adapted to the steam cylinders of a locomotive engine. In these figures, A is the steam cylinder which is of the ordinary construction and is fitted 45 with a piston and piston rod in the usual manner; B is the connecting rod which imparts motion from the piston rod to the crank C secured to the crank shaft. The valves of this engine are contained in a 50 valve chest D secured to the upper side of the steam cylinder and are two in number. The lower valve E regulates the admission and discharge of steam to and from the steam cylinder, and is moved directly by 55 steam from the boiler whenever the piston nears either extremity of the steam cylinder.

The upper valve G, which slides upon the lower, regulates the flow of steam from the boiler to actuate the lower valve and is also constructed in such manner that it cuts off 60 the supply of steam to the steam cylinder when the piston has accomplished a part of its stroke, thus permitting the steam in the cylinder to act expansively. The lower or main steam valve has the form of a rectangular block and slides upon a seat, secured to the upper side of the steam cylinder. This seat is pierced with two steam ports a, b, and with an exhaust port, c. The former communicates by means of the steam 65 passages d, d with the extremities of the cylinder to which they are respectively adjacent. The exhaust port c communicates with the exhaust passage H, by which the spent steam is conducted to the exhaust pipe. 70 The lower face of the main steam valve is pierced with two steam passages e, f and with a cavity g, which forms the communication between the exhaust port and the steam port of that extremity of the cylinder 75 from which the steam is exhausting. The steam passages e, f are extended through the valve and terminate in ports at the upper face thereof. This steam valve is fitted as in the ordinary manner to slide steam 80 tight upon its seat on the cylinder. Its sides are also fitted to slide steam tight against the adjacent sides of the steam chest or steam packing is inserted between the two, so that the steam valve constitutes a 85 species of piston by which the one extremity of the valve chest is separated from the other. The upper valve G has also the form of a rectangular block. Its lower face slides upon the upper face of the main 90 steam valve beneath. One of its sides is fitted to slide steam tight against the adjacent side, h, of the valve chest, and its opposite side is either fitted to slide steam 95 tight against the adjacent side of the steam chest, or steam packing is inserted between the two, and its upper face slides steam tight against the lower face of a self adjusting ajutage J, which is inserted through the top, k, of the valve chest, its sides being 100 packed to prevent the passage of steam to the valve chest otherwise than through the ajutage.

The upper valve G is pierced with a passage m which extends transversely through 110 it, and terminates in ports in its upper and lower faces respectively. As this valve is

constructed to cut off the supply of steam from the boiler when the steam piston has accomplished only a portion of its stroke, the port in the lower face of the valve is of about the same dimensions as the ports in the upper face of the main valve beneath. The object of the upper port in the upper valve is to form a communication between each extremity of the valve chest, and the ajutage, *J*, in alternate succession. This port therefore is of such width that as the upper valve nears each extremity of its stroke the outer edge of the port passes beyond the outer edge of the lower face of the ajutage, as shown at Fig. 1, thus permitting the steam from the ajutage to pass to that extremity of the valve chest toward which the valve is moving at the time. That side face, *h*, of the valve chest against which the upper valve slides is pierced with two ports *i*, each of which occupies such a position with respect to the adjacent extremity of the upper valve that when this valve is in a position to allow steam to pass by means of its upper port to one extremity of the valve chest the lateral port, *i*, of the opposite extremity of the valve chest is uncovered. These lateral ports communicate with the exhaust pipe by means of lateral passages whose position is shown by red lines in Fig. 1.

The upper valve, *G*, is caused to move to and fro by means of an eccentric *L* upon the crank shaft with which the valve is connected by means of a suitable rod *n*, arms *p*, *p*, rock shaft *r*, and valve stem *s*, and the eccentric is set at such an angle to the crank that the upper valve is moved to admit steam into that extremity of the valve chest toward which the piston is moving just before the latter arrives at the extremity of its stroke. When therefore the engine is at work and the piston is moving in the direction indicated by the arrow, *t*, in Fig. 1, the upper valve is moved to the position in which it is represented in this figure just before the piston reaches the extremity of its stroke. As the upper valve arrives at this position the port in its upper face permits steam to pass from the ajutage, *J*, into the extremity of the valve chest, while at the same time the lateral exhaust port, *i*, leading from the other extremity of the valve chest is uncovered. The steam entering the valve chest presses upon the head of the main steam valve as upon a piston, and as the pressure upon the opposite head of the valve is merely that of the exhaust passage, with which this extremity of the valve chest is in communication, through the lateral exhaust port, *i*, the main steam valve is forced with the whole pressure of the steam toward the opposite extremity, *u*, of the valve chest by which movement its steam passage, *f*, is made to correspond in position with the

steam port, *b*, of the steam cylinder, while the cavity, *g*, in its lower surface at the same time forms a communication between the port, *a*, of the opposite extremity of the cylinder and the exhaust port *c*. The piston and valve now occupy the positions in which they are respectively represented at Fig. 2, hence the steam from the boiler passing through the ajutage *J*, the passage, *m*, in the upper valve and the steam passage, *f*, in the lower valve, enters the cylinder through the steam port, *b*, and the steam passage appertaining thereto, and acts upon the head, *z*, of the piston, while such steam as may be in the cylinder at the opposite side of the piston exhausts freely therefrom. As the piston begins to retrograde in the direction indicated by the arrow, *v*, the eccentric turning with the crank shaft moves the upper valve in the same direction as the piston, and as the main steam valve remains stationary during this movement of the upper valve the latter gradually passes over its upper face and in the example here represented closes the upper port of the steam passage, *f*, when the piston has accomplished half of its retrograde stroke (the piston and valves now occupying the positions in which they are respectively represented at Fig. 3) by which means the communication between the boiler and the steam in the cylinder is cut off and the latter is permitted to act expansively upon the piston. As the piston continues to retrograde the upper valve is moved onward, and as the piston nears the extremity of its retrograde stroke, the upper valve is brought into a position to admit steam into the extremity of the valve chest *u*, while by the same movement the lateral exhaust port *i* leading from the opposite extremity, *w*, of the valve chest is uncovered. The steam from the boiler now forces the main steam valve to move in a direction the reverse of that in which it moved during the preceding stroke of the piston, the passage, *e*, is brought into correspondence with the port, *a*, of the cylinder from which steam has just been exhausting while the cavity, *g*, in the lower face of the valve forms a communication between the opposite port, *b*, of the cylinder and the exhaust passage; hence a fresh quantity of steam from the boiler is admitted to act upon the head *z*, of the piston, while the steam on the opposite side of the piston is permitted to exhaust freely as before. This new supply of steam from the boiler is cut off in the same manner as that supplied during the preceding stroke of the piston by the covering of the passage in the lower valve by the face of the upper valve as the latter is moved by its eccentric toward the opposite extremity of the valve chest.

From the above description it is clear that the main steam valve is moved at intervals,

and that the movements occur whenever the piston reaches either extremity of its stroke; and as the movement is effected by the pressure of the steam upon one head of the valve 5 and is resisted merely by the pressure of the exhaust upon its opposite head and by the friction of the valves, the movement will be effected with great velocity, hence the exhaust and steam ports will be opened almost 10 instantaneously. The movement of the valve in each direction is limited by a spring bumper, y , affixed to the inner face of the valve chest, whose elasticity breaks the force of the blow or concussion caused by the 15 sudden stoppage of the valve.

Instead of employing the bumpers y to deaden or break the concussion produced by the sudden stoppage of the valve, a quantity of steam or air may be employed for the 20 purpose by inclosing the same in a recess at the end of the valve, so that it will be compressed as the valve nears the end of its stroke and by its resistance to compression will lessen or break the concussion.

25 In the engine, portions of which are represented at Fig. 4, the arrangement of the valves is somewhat different from the foregoing. The lower valve E as shown in this figure is fitted to move in a cavity formed in 30 the lower face of the upper valve, G , whose construction does not vary materially from that of the ordinary short slide valve. One of the sides of the inner valve is fitted to slide steam tight against the inner face of 35 the adjacent side of the outer valve. The spaces between the opposite side and the top of the inner valve and the adjacent inner faces of the outer valve are packed as shown at c in the drawing. The cavity of 40 the outer valve therefore acts as a valve chest within which the inner valve is moved to and fro like a piston by the pressure of steam alternately upon its opposite extremities. The exhaust of the steam alternately 45 from each extremity of this cavity is effected through ports i , i , which communicate with passages in the outer valves that conduct the steam to the exhausting cavity, g , of the inner valve. The admission of steam 50 alternately to the opposite extremities of the inner valve is effected by making the covering portions, l , l , of the outer valve of less width than the ports, a , b , over which they move, hence whenever the upper valve be-

gins to open either steam port, the steam 55 passes around beneath the covering part of the valve and enters the adjacent extremity of the cavity or steam chest within which the inner valve is contained as shown by the arrow, q , in the drawing. 60

The valve gear I have thus far described is arranged to work when the piston is driving the crank shaft in one direction. They may be fitted to work equally well when the movement of the crank shaft is to 65 be reversed by reversing the movement of the upper valve either by means of a second eccentric affixed to the crank shaft at a suitable angle with the crank, as represented in red lines in Fig. 4, or in any other of the 70 well known methods in use for reversing the valves of steam engines. The last arrangement of valves is adapted only to the sudden opening of the exhaust, as the admission of steam is regulated wholly by the upper 75 valve, but this arrangement of valve may be modified to effect the sudden admission of steam also, by extending the face of the lower valve at each extremity beneath the 80 extremities of the upper valve, so that the upper faces of these extended portions of the lower valve form seats on which the extremities of the upper valve slide. Suitable ports must also be made in these faces to permit the steam to pass into either 85 extremity of the cavity of the upper valve when the lower valve is to be moved. The upper valve in this case as well as in that first described may be made to effect the cutting-off of the steam by forming passages 90 in the lower valve which will be covered at the proper moment by covering portions of the upper valve.

What I claim as my invention and desire 95 to secure by Letters Patent, is—

The arrangement in the valve chest of a steam engine, of a duplex valve one part of which is actuated in the usual manner by valve gear to admit steam from the boiler to act directly on the other part and force 100 it to open and close the steam or exhaust passages, substantially as herein described.

In testimony whereof I have hereunto 105 subscribed my name.

MATTHIAS W. BALDWIN.
